UNITED STATES PATENT OFFICE

158,388

COMBINED SCRAPER AND HOLDER FOR BRUSHES

Herman H. Kistner, Glen Ridge, N. J.

Application December 10, 1948, Serial No. 150,090

Term of patent 14 years

(Cl. D9—2)

To all whom it may concern:

Be it known that I, Herman H. Kistner, a citizen of the United States, residing in Glen Ridge, in the county of Essex and State of New Jersey, have invented a new, original, and ornamental Design for a Combined Scraper and Holder for Brushes, of which the following is a specification, reference being had to the accompanying drawing, forming a part thereof.

Fig. 1 is a perspective view of a combined scraper and holder for brushes embodying my new design.

Fig. 2 is an end elevational view thereof, taken on line 2—2 of Fig. 1, and

Fig. 3 is a bottom plan view thereof, taken on line 3—3 of Fig. 1.

The dominant features of the present design reside in the portions shown in full lines in the accompanying drawing.

I claim:

The ornamental design for a combined scraper and holder for brushes, as shown and described.
HERMAN H. KISTNER.
